UNITED STATES PATENT OFFICE

1,930,574

TUFTING TABLE APPARATUS

Harry E. Wolf, Pittsburgh, Pa.

Original application May 31, 1930, Serial No. 458,744, Patent No. 1,883,220, October 18, 1932.
 Divided and this application July 13, 1932.
 Serial No. 622,213

13 Claims. (Cl. 45—138)

My invention relates to the art of mattress making, and it has special reference to tufting tables for such purposes, this application being a division of my Patent No. 1,883,220, dated 5 October 18, 1932.

One object of my invention is to provide a tufting table having a perforated bottom member and a removable top member, with relatively small openings, substantially aligned with the respective perforations in the bottom member.

A second object of my invention is to provide a tufting table, having a top and bottom member for enclosing the mattress being worked upon, that may be rotated with respect to an 15 upright frame, and the parts locked in position, irrespective of whether the apparatus occupies its normal or its inverted position.

Another object of my invention is to provide a table of the character set forth, so arranged that 20 the centers of the openings in the top and bottom members may substantially exactly register each time that the apparatus is assembled.

A further object of my invention is to provide a tufting table having cooperating oppositely disposed table members, the assembly being capable 25 of rotation to bring either member uppermost.

Other objects of my invention will become evident from the following detailed description, 30 taken in conjunction with the accompanying drawings, wherein,

Figure 1 is a view, in front elevation, of a tufting table organized in accordance with my present invention, and

Figure 2 and Figure 3 are views, in top plan 35 and in end elevation, respectively, of the apparatus shown in Figure 1.

Referring to the drawings, the tufting table here shown comprises a pair of transverse frame members 1, which may constitute standard T- 40 irons and which are respectively supported on pairs of legs 2, which may be formed of channel irons, for example. A bottom table member proper 8, and an upper table member 13, interlock with each other and are pivotally supported on the frame members 1, being capable 45 of being locked in position by means of suitable pivot locks 6.

The transverse frame members 1 may be secured by means of bolts 3, to the legs 2, which in 50 turn, may be secured to the floor by small angle irons 4, bolted to the lower ends of the legs.

Hubs or bearings 5 are bolted to the middle portion of each of the transverse frame members 1, for the purpose of providing a pivotal bearing 55 for the lower table member 8. Preferably,

the illustrated pivot pin extends a short distance into the bottom table member 8, being suitably reinforced by means of plates 5a. By reason of this pivotal connection, the table member 8 and its associated parts, namely, the top 60 table member 13, and the intervening mattress 25 being worked upon, may be readily rotated from its normal to its inverted position by a light touch of the hand.

To insure that the table members are locked 65 in position when it is desired to work upon the mattress, a pair of the pivot locks 6 are mounted, by means of pivot pins or bolts 7, on each of the transverse frame members 1, about half way between the bearing 5 and the ends of the frame 70 member. Each of these pivot locks is provided with a suitable handle 6a, and the inner end is bifurcated to grip either the bottom member 8 in either a normal or an inverted position, as the case may be, and thus hold the rotatable table 75 assembly in the desired operative position. For the purpose of preventing undue wear, by the use of these pivot locks, reinforcing plates 10 are preferably secured to the bottom table member 8, in the positions where the bifurcated inner 80 ends of the pivot locks engage the bottom table member.

The bottom table member 8 is made from any suitable material, such as wood, the inner face being provided with a suitable veneer 9. 85 Similarly, the inner face of the top table member 13 is provided with a suitable veneer 14. The bottom member 8 has a number of relatively large holes 12, drilled through it for the purpose of permitting tying of tufting material to 90 form a tuft, after the tapes or other material have been threaded through, as subsequently described.

The top member 13, on the other hand, is provided with an equal number of relatively small 95 openings or slots 21, having a circular or enlarged center, for a purpose to be hereinafter set forth. The registration of the centers of each of the small slots or openings in the top member with the centers of the large openings 100 in the bottom member, is insured by means of suitable male and female centering posts 11 and 20. A pipe or hollow post 11 is secured to each corner of the upper side of the bottom plate member 8, and a pin or solid post 20 is secured 105 to each corner of the lower face of the upper table member 13. These pins and hollow posts are adapted to engage when the top and bottom members are in operative position, whereby the desired registration of the openings in the 110

top and bottom table members is readily effected each time the apparatus is being used.

The top table member 13 is provided with reinforcing metallic strips or the like 15, at the ends thereof on the upper side, and a plurality of cables 16, are secured to screw eyes 16a in each of the plates 15, at the corners, the four cables being joined at the center to a hook 17, and a single cable passing from the hook over a pulley 18, which is suitably attached to the ceiling or other support (not shown). The purpose of this arrangement is to permit the top table member 13 being readily raised when the mattress is being laid on the bottom table member 8, or taken off it, and also to permit readily placing the top table member on the mattress and effecting the proper positioning of the member 13, by means of the centering posts 11 and 20.

For the purpose of holding the top and bottom table members in suitable position with respect to the mattress 25, a plurality of clamps 26 are passed over the sides of the top and bottom table members, at suitable intervals, thereby compressing the mattress to the desired thickness, and placing the entire apparatus in the best possible condition to insure rigid, accurate and neat workmanship in threading the tufting needles therethrough, as set forth in my above-identified parent application.

Assuming that the top table member 13 occupies its suspended position near the ceiling, and that the bottom table member 8 occupies the position shown in the right hand side of Figure 2, with the pivot locks 6 in the illustrated locked position, the operation of the apparatus may be set forth as follows.

The mattress 25 to be worked upon is laid upon the bottom table member 8, and lined up with the edges thereof. The top table member 13 is then lowered into position, with the four pins 20 passing through the four hollow posts 11. The clamping members 26 are then placed in position and the apparatus is ready for the use of the needle device shown in my above-identified parent application.

To finish the tufting of the mattress, the four pivot locks 6 are moved out of operating position, the top and bottom table members with the mattress between them are rotated to an inverted position, and further tufting operations are carried on, as set forth in my above-identified parent application, without in any way disturbing the tufting table parts. It will be understood that to lock the table in such inverted position, the pivot locks 6 are again brought into play, to then grip the bottom table member 8, in its inverted position.

The pivot locks are then again removed, the table members and mattress rotated to normal position, the clamps 26 removed, and the top member 13 pulled upwardly, whereupon the finished mattress 25 may be removed and another one put in its place.

It will be seen, therefore, that I have provided a simple and inexpensive tufting table for producing quick, convenient and accurate tufting of a mattress.

I do not wish to be restricted to the specific structural details or arrangement of parts herein set forth, as various modifications of my apparatus may be made without departing from the spirit and scope of my invention. I desire, therefore, that only such limitations shall be imposed thereon as are indicated in the appended claims.

I claim as my invention:

1. A tufting table comprising an upright frame, a bottom perforated member adapted to support a mattress, means for pivotally securing said member to said frame, a plurality of locking devices pivoted on said frame for locking said member in position, a perforated removable top member for laying on the mattress, and male and female centering posts on said members for positioning the centers of the openings in the top members substantially concentrically with the centers of the openings in the bottom member, said locking devices being also adapted to lock said bottom member in an inverted position when the top and bottom members and the mattress are rotated on said pivotal means. 80 85 90

2. A tufting table comprising a frame, a bottom member adapted to support a mattress, a top member for laying thereon, male and female centering posts for holding said members in proper alignment with respect to the mattress, and means for pivotally securing said bottom member to said frame to permit rotation of said members and mattress along an intermediate axis thereof. 95 100

3. A tufting table comprising a frame, a bottom member adapted to support a mattress, a top member for laying thereon, means for holding said members in position with respect to the mattress, means for permitting rotation of said members and mattress relative to said frame to bring either side of the mattress uppermost, and the same horizontally swingable means for locking said members to said frame in either selected position. 105 110

4. A tufting table comprising a frame, an apertured bottom member adapted to support a mattress, an apertured top member for laying thereon, means for holding said members in proper alignment on the mattress, means for permitting complete rotation of said members and mattress relative to said frame to allow ready operation on the respective sides of the mattress through the apertures of the said bottom and top members, and the same means for locking said members and mattress with either said bottom or said top member uppermost, said locking means being secured to said frame and pivoting about a vertical axis. 115 120 125

5. A tufting table comprising a frame, a bottom member adapted to support a mattress, a top member for laying thereon, a plurality of concentrically related means for holding said members in position with respect to the mattress, means for pivotally securing one of said members to said frame to permit rotation of said members and mattress along an intermediate axis thereof, and horizontally swingable means for locking said members and mattress to said frame with either said bottom or said top member uppermost. 130 135

6. A tufting table comprising a frame, a bottom member adapted to support a mattress, a top member for laying thereon, a plurality of registerable means for holding said members in proper alignment with respect to the mattress, means for pivotally securing said bottom member to said frame to permit rotation of said members and mattress along an intermediate axis thereof, and means pivoted on said frame and about a vertical axis for locking said members and mattress with either said bottom or said top member uppermost. 140 145

7. A tufting table comprising a frame, cooperating oppositely disposed table members, means 150

for permitting rotation of said members to bring either one uppermost, and the same horizontally swingable means for locking said members to said frame in either selected position.

- 5 8. A tufting table comprising a frame, co-operating top and bottom table members, means for pivotally securing said bottom member along an intermediate axis thereof to said frame, and the same means for locking said members in position with either said top or said bottom member uppermost, said locking means being secured to said frame and pivoting about a vertical axis.
- 10 9. A tufting table comprising an upright frame, a bottom member adapted to support a mattress, means for pivotally securing said member to said frame, comprising a bifurcated member pivoted on said frame for locking said member in position, a removable top member for laying on the mattress, and means for substantially exactly positioning said top member relative to said bottom member, said locking means being also adapted to lock said bottom member in an inverted position when the top and bottom members and the mattress are rotated on said pivotal means.
- 15 10. A tufting table comprising an upright frame, a bottom perforated member adapted to support a mattress, means for pivotally securing said member to said frame, comprising a bifurcated member pivoted on said frame for locking said member in position, a removable top member for laying on the mattress, and male and female centering posts on said members for positioning the centers of the openings in the

top members substantially concentrically with the centers of the openings in the bottom member, said locking devices being also adapted to lock said bottom member in an inverted position when the top and bottom members and the mattress are rotated on said pivotal means. 80

11. A tufting table comprising a frame, a bottom member adapted to support a mattress, a top member for laying thereon, means for holding said members in proper alignment with respect to the mattress, means for pivotally securing said bottom member to said frame to permit rotation of said members and mattress along an intermediate axis thereof, and means comprising a bifurcated member pivoted on said frame for locking said members and mattress with either said bottom or said top member uppermost. 85

12. A tufting table comprising a frame, co-operating oppositely disposed table members, means for permitting rotation of said members to bring either one uppermost, and means comprising a bifurcated member pivoted on said frame for locking said members in either selected position. 90

13. A tufting table comprising a frame, co-operating top and bottom table members, means for pivotally securing said bottom member along an intermediate axis thereof to said frame, and means comprising a bifurcated member pivoted on said frame for locking said bottom member in either a normal or an inverted position. 100
